Inventor,

Frederick Wittram

United States Patent Office.

FREDERICK WITTRAM, OF SAN FRANCISCO, CALIFORNIA.

Letters Patent No. 97,261, dated November 23, 1869.

IMPROVED DEVICE FOR RELEASING STANDING RIGGING.

The Schedule referred to in these Letters Patent and making part of the same.

To whom it may concern:

Be it known that I, FREDERICK WITTRAM, of the city and county of San Francisco, State of California, have invented certain new and useful Improvements in Standing Rigging for Vessels; and I hereby declare that the following is a full, clear, and exact description thereof, reference being had to the accompanying drawings, making part of this specification, in which—

Figure 1 is an elevation, or broadside view.

Figure 2, an end view.

Figure 3, a plan view.

The letters of reference indicate the same parts in the different figures.

My invention relates to securing shrouds, backstays, and other standing rigging, to the plates or to the sides of a vessel, in such a manner and by such devices that two or more may be disengaged or "let go" simultaneously, or nearly so. It is peculiarly adapted to wire rigging, or to that composed in whole or in part of rods or chains, not easily cut by an axe, or other ordinary means. It will also be found useful, with the ordinary hemp rigging, in many of the emergencies to which sea-going vessels are liable.

The following is a description of my invention:

A is a horizontal bar, capable of longitudinal motion, through the agency of any convenient mechanical devices.

Bent arms, B, are attached to the bar A, at suitable distances, designed to act as bolts or pins, by which the eyes C, at the lower ends of the shrouds, are secured to the shackles D, formed upon the upper ends of the plates E.

The number of arms B correspond with the number of shrouds, or other standing rigging, which stand

in the same vertical and horizontal plane, or which it may be desirable to render capable of being let go simultaneously. In operation, the bolts or arms B, being in position, as shown in fig. 1, are simultaneously released, when required, by drawing back the bar A, and withdrawing all the bolts at once.

The advantages of my invention will be apparent to sea-faring men. As one instance of its usefulness and value, suppose a mast carried away by the parting of the weather-rigging, it becomes an urgent necessity to get rid of the wreck before the side or counter of the ship is stove in; or, in the case of a steamship, the side-wheel or propeller-screw hopelessly fouled or injured, the application of my invention relieves the ship at once from this difficulty and danger.

A vessel, thrown on her beam-ends by the force of the wind, may be saved from impending destruction, by being enabled to get rid of one or more of her masts with facility, after the standing rigging has been let go by my invention.

I do not confine myself to the use of any mechanical device for withdrawing the bolts which release the rigging; but

What I claim as my invention, and desire to secure by Letters Patent, is—

The combination and arrangement of devices, as herein described, or any equivalent means, by which two or more shrouds, or other parts of standing rigging, can be simultaneously released or "let go," as specified.

FREDERICK WITTRAM.
